(57) **CLAIM**

The ornamental design for a compact utility knife with fixed spring lever, as shown and described.

DESCRIPTION

FIG. 1 is a right top perspective view of the compact utility knife with fixed spring lever;

FIG. 2 is a top plan view with blade inserted thereof;

FIG. 3 is a front elevation view thereof,

FIG. 4 is a back elevation view thereof,

FIG. 5 is a left elevation view thereof; and,

FIG. 6 is a right elevation view thereof.

The broken line showing of the utility knife blade in FIG. 2 is provided for purposes of environment and forms no part of the claimed design.

The bottom plan view is a mirror image of the top plan view in FIG. 2, and, therefore, is not shown.
